UNITED STATES PATENT OFFICE

1,969,195

CONTAINER

Philip D. Archer, Hollywood, Calif., assignor to
 Campbell-Taggart Associated Bakeries, Inc.,
 Kansas City, Mo., a corporation of Delaware

Application July 28, 1932, Serial No. 625,435

3 Claims. (Cl. 206—44)

My invention relates to containers and more particularly to a device of that character for protecting cakes and similar baked products during transportation and display.

5 An important object of my invention is to provide a container so constructed that a formed cake mounted therein is maintained, with the exception of its lower edge, in spaced relation with the side walls of the container to protect the 10 side edges of the cake against marring.

Another object is to provide means for readily applying and securely retaining a flexible transparent cover on a box element of the container for displaying the contents of the box in a sanitary manner.

15 A further object of the invention is to provide a strong and readily assembled container that is inexpensive to manufacture.

In accomplishing these and other objects of 20 my invention I have provided improved details of structure, the preferred form of which is illustrated in the accompanying drawings, wherein:—

Fig. 1 is a perspective view of an assembled container embodying my invention, with parts 25 broken away for better disclosure.

Fig. 2 is a longitudinal section of the container on the line 2—2 Fig. 3, showing a cake in side elevation.

Fig. 3 is a cross section on the line 3—3 Fig. 2, 30 with the cake shown in end elevation.

Fig. 4 is a perspective view of the container parts in disassembled but related condition, a portion of the box element being broken away to better illustrate its construction.

35 Referring more in detail to the drawings: 1, 2, 3 and 4 designate respectively the box element, support or tray, cover and collar comprising the four elements of the container.

The box or body member is preferably constructed of a formed sheet 5 of cardboard or equivalent material scored along longitudinal and transverse lines 6 and 7 to define a rectangular bottom 8. The remainder of the longitudinal score lines are cut to divide the portion surrounding the bottom into side and end wings 9 and 10, while the terminating portions of the transverse score lines produce lateral flaps 11 on the side wings. The end wings extend from the bottom to a distance more than twice that of the 40 side wings and are scored at their approximate centers on lines 12 to form flap portions 13 adapted to be bent inwardly and overlap the lateral flaps of the side wings when these have been bent to a right angular position in relation to the bottom. Formed on the flap portions 13 adjacent

their extreme outer ends are score lines 14 defining foot portions 15 for engaging the bottom when the box is in assembled condition.

In order to anchor the collar 4, later more fully described, to the box, incisions or slits 16 are cut into the end wings adjacent their bottom edges in a manner to produce T shaped locking tabs 17 having lateral tongues 18. The end wings are further provided with apertures 19 bisected by the score lines 12 to form semicircular notches 20 in the folded upper edges of the end wings for a purpose presently disclosed.

The second element 2, designated a support, consists also of a sheet of cardboard or the like preferably impregnated with paraffin or the like 25 to prevent adherence to or discoloration by a cake or the like 20 placed therein and is scored along longitudinally and transversely extending lines 21 and 22 to define a bottom 23 of smaller dimensions than the bottom of the box portion as 30 best shown in Figs. 2 and 3. The margin surrounding the bottom is cut out at the corners 35 of the sheet to provide side and end wings 24 and 25 having outwardly tapering end edges 26, the edges of the side wings terminating in 40 straight portions 27 parallel with the transverse score lines for engaging the end wings of the box to prevent longitudinal movement of the support therein.

For the cover element 3 a flexible sheet of material is used that is preferably transparent, very thin, and difficult to tear, regenerated cellulose serving excellently for this purpose.

The collar 4 comprises a cardboard or like strip of a width substantially equal to the height of 45 the box element and scored along transverse lines 28 to produce side and end walls 29 and 30 and to facilitate bending of the strip into a rectangular collar having inside dimensions corresponding to the outside dimensions of the box. The ends of 50 the strip overlap as indicated at 31 and may be secured together in any suitable manner.

Provided in the end walls of the collar adjacent their lower edges are paired slits 32 for receiving the tongues of the locking tabs to anchor 55 the collar to the box element.

Assuming a container to be constructed as described the order of assembling the elements would be as follows:

After the box has been folded the support is 60 mounted therein with the upper edges of its side and end wings engaging the corresponding walls of the box. Obviously the cake may be mounted on the support bottom before or after the support is placed in the box, and the sides of the 65

cake will be maintained in spaced relation to the support wings due to the outward inclination of the wings thereby avoiding marring of the cake sides, a feature particularly desirable when such 5 sides are coated with icing.

The flexible sheet, having an area greater than that of the horizontal cross section of the box, is placed on the cake with its margin extending beyond the side and end edges of the box and the 10 collar is sleeved downwardly over the cover margin and box to secure the cover in tautened condition against displacement and to reinforce the box. The tongues of the locking tabs are finally inserted in the respective slits of the collar and 15 the container and its contents are ready for transportation and display.

To remove the cake from the container the foregoing order is reversed, the semicircular notches in the upper edges of the box ends facilitating 20 grasping of the collar and support wings for removal from the box.

What I claim and desire to secure by Letters Patent is:

1. In a device of the character described, a 25 box having a bottom and side and end walls, and a support in the box having a bottom of less area than the bottom of the box and having side and end wings provided with outwardly tapering end edges, the end edges of the side 30 wings terminating in straight portions for engaging the end walls of the box to prevent longitudinal movement of the support in the box.

2. In a device of the character described, a box provided with a rectangular bottom and side walls having interengaged ends to form corners of the box, a tray in the box having a rectangular bottom of less area than the bottom of the box and outwardly flaring side wings having ends engaging in the corners of the box at a point spaced above said bottom of the box whereby the bottom of the tray is prevented from movement in the box, a cover for the box extending across the edges of the side walls adjacent the wings of the tray to limit vertical movement of the tray in the box, and a collar engaging with the cover and side walls of the box to retain the cover and support the side walls of the box in engaging relation with the wings of the tray. 80 85 90

3. In a device of the character described, a box provided with a rectangular bottom and side walls having interengaged ends to form corners of the box, a tray in the box having a rectangular bottom of less area than the bottom of the box and outwardly flaring side wings having upper edges extending in parallel and co-extensive relation with the upper edges of the side walls to engage in the said corners, selected side wings of said tray being cut to conform to the flare of the adjacent wings, a cover extending over the edges of the side walls of the box and the upper edges of the side wings of the tray, and a collar engaging the side walls of the box to retain said 100 105 110 cover. 115
